UNITED STATES PATENT OFFICE.

SARAH R. ANDERSON, OF SOUTHERN PINES, NORTH CAROLINA.

OPENER.

1,277,818.

Specification of Letters Patent. Patented Sept. 3, 1918.

Application filed May 20, 1918. Serial No. 235,512.

To all whom it may concern:

Be it known that I, SARAH R. ANDERSON, a citizen of the United States, residing at Southern Pines, in the county of Moore and 5 State of North Carolina, have invented new and useful Improvements in Openers, of which the following is a specification.

This invention relates to an implement for facilitating the removal of caps or covers 10 from fruit jars or the like.

From experience I have found that a slight pressure exerted between the cover and jar, sufficient to permit of a slight passage 15 of air between these members permits of the ready separation thereof, both the jar and its cover being frequently constructed of glass, such pressure should not be too pronounced.

It is the object of the present invention 20 to produce a point prying element loosely associated with a handle so that the same is susceptible to a slight movement inward of the handle, the element being under the influence of a spring, the tension of which may 25 be readily regulated to limit the sliding movement of the prying element with respect to the handle, so that the device may be successfully employed in the successive steps necessitated in removing a cap or cover 30 from a jar.

Other objects and advantages will appear as the nature of the invention is better understood, reference being had to the accompanying drawings, in which,

35 Figure 1 is a perspective view illustrating the operation of the improvement in removing a cap or cover from a jar.

Fig. 2 is an approximately central longitudinal sectional view through the same.

40 As disclosed by the drawings I employ a wedge-shaped pry which is indicated by the numeral 6. On the inner end of the wedge 6 is formed a shank 7 that has its end headed as at 8, and this head end of the shank is received and guided by a sleeve 9 arranged longitudinally through a handle 10. The outer end of the sleeve 9 is closed so that the 45 head 8 cannot pass therethrough, and the head is contacted by a helical spring 11 received in the sleeve 9. This spring 11 is

guided by a rod 12 which is of a less length than the sleeve 9. The rod 12 is received in an inner concaved or recessed portion 13 of a knob or push member 14, the rod being secured to the said member 14.

55

It will be apparent that the spring exerting a tension against the head 8 permits of the yielding of the wedge or pry member 7 when the same is arranged between a jar and a cover therefor. Should it be required that the pressure between the wedge and the jar and cover be determined or non-yielding, the operator places his hand on the outer end of the handle forcing the element 14 inward of the sleeve 9, and causing a partial contraction of the presser spring 11 between the said element 14 and the head 8 of the wedge member, holding the wedge member against free longitudinal movement, or, in other words, locking the wedge member to the 70 handle.

60

It is believed, from the foregoing that the simplicity and advantages of the construction will be apparent without further detailed description.

75

Having thus described the invention, what I claim is:

1. In a device for the purpose set forth, a hollow handle, a wedge member having a headed shank received in said handle, a 80 spring element in the handle contacting with the head of the shank, a longitudinally movable presser element for said spring projecting through one end of the handle, and means for limiting such longitudinal movement of said element.

85

2. In a device for the purpose set forth, a wedge member provided with a headed shank, a hollow handle receiving the head of said shank, means on said handle for holding said shank against outward movement, a spring in the handle contacting with the head of the shank, and an element extending through the handle and co-engaging with the spring and adapted, when moved inward of the shank to increase the pressure of the spring against the head of the shank.

90

95 In testimony whereof I affix my signature.

SARAH R. ANDERSON.
